(57) **CLAIM**

The ornamental design for a surface configuration of a gear lever plate for a vehicle, as shown and described.

DESCRIPTION

FIG. 1 is a perspective view of a surface configuration of a gear lever plate for a vehicle according to my novel design; and,

FIG. 2 is a top view of the surface configuration of a gear lever plate for a vehicle according to my novel design.

The broken lines included depict environment and are not part of the claimed design.
